UNITED STATES PATENT OFFICE.

ELMER U. AMES, OF PHILADELPHIA, PENNSYLVANIA, ASSIGNOR TO H. BRINTON COMPANY, OF PHILADELPHIA, PENNSYLVANIA, A CORPORATION OF PENNSYLVANIA.

TRANSFER MECHANISM FOR KNITTING-MACHINES.

1,297,632.

Specification of Letters Patent. Patented Mar. 18, 1919.

Application filed December 29, 1915. Serial No. 69,260.

To all whom it may concern:

Be it known that I, ELMER U. AMES, a citizen of the United States, residing in Philadelphia, Pennsylvania, have invented 5 the Transfer Mechanism for Knitting-Machines, of which the following is a specification.

One object of my invention is to provide a method involving a novel series of steps 10 for preparing a circular knitting machine for transferring, the invention also contemplating the provision of simple, substantial and efficient means for carrying out such method including a device for automatically 15 moving the latch ring or yarn changer at a definite time in the operation of the machine, to prevent its engagement with the sinker movement or with the parts associated therewith.

20 I also desire to provide a novel arrangement of cams and cam controlled mechanism for preparing a knitting machine for the transferring operation.

These objects and other advantageous ends 25 I secure as hereinafter set forth, reference being had to the accompanying drawings, in which,

30 Figure 1 is a side elevation, partly in vertical section, taken through the longitudinal center line of the cylinder of a circular knitting machine, showing my invention as applied thereto;

35 Figs. 2 and 3 are elevations partly in section illustrating certain of the parts of the machine in different positions occupied under operating conditions;

40 Figs. 4 and 5 are fragmentary elevations of the yarn guides and certain parts associated therewith, illustrating the needles in the positions assumed under certain conditions of operation, and

45 Figs. 6, 7 and 8 are diagrammatic elevations showing the positions assumed by certain of the cams and by the needles controlled thereby, during the operation of my invention.

50 While the mechanism constituting this invention may be applied to circular knitting machines of various types, it is preferably used with a machine of substantially the construction described and claimed in my application for U. S. Patent, Number 7,111, filed February 9, 1915, which illustrates and describes the various structures supporting

and coöperating with the apparatus shown 55 in the drawings above referred to. In these drawings, 1 represents a portion of the main frame of a knitting machine which provides a bearing for a shaft 2 carrying a cam drum 3, and likewise has a bearing for the support of a rotary cylinder 4 which may be driven by the well known mechanism, such as is shown in my application above referred to.

The cylinder has mounted upon it a sinker 65 movement including a sinker ring 16^a, sinkers 16, and a sinker cam ring 15 with its cams for operating said sinkers. The cylinder also supports short butt needles 5 and long butt needles 6 which are held in their 70 grooves by retaining coil-springs 7 and are acted on by a number of cams supported by a non-rotatable cam ring 8. Said ring is mounted on or formed as part of a vertically extending post 9 slideable in a guideway 10 suitably formed in the frame 1 and carried upon a spring 11 coiled around and concentric with said guideway. The ring with its cams may be vertically moved with reference to the cylinder 4 under the action 75 of a suitable cam 12 on the drum 3, through the medium of a lever 13 connected to the post 9 by a link 14. Said post 9 also serves to support a collar 17 which is adjustably held to the top thereof by a set screw 18, 80 shown in dotted lines in Fig. 1.

This collar has upwardly extending forks between which is pivoted or trunnioned an arm 19 in the form of a flat plate having side members and integral with or rigidly 90 connected to a latch ring 20 which is thus supported so that it is normally concentric with the needle cylinder 4. In the channel defined by the flat bottom and the two side members of this arm 19 are slidably mounted 95 a series of jacks, of which two are indicated at 21 and 22, each having a pair of elongated slots 23 for the reception of pins 24 extending between the side members of the arm 19 so as to limit their movement. Said jacks 100 are normally held in or tend to return to positions distant from the cylinder 4 under the action of springs 25 and each of them acts upon a yarn feeding finger, of which five are shown in Figs. 4 and 5, at 26, 27, 28, 105 29 and 30.

For controlling the positions of these fingers I provide a series of levers, of which

two are indicated at 31 and 32, each of which has a vertically extending arm including a plane portion designed under certain conditions to coöperate with the curved 5 outer end of one of the jacks. The other arm of each of the levers is designed to be acted on by cams on the drum 3, and in the present case I have illustrated the lever 31 as having its arm engaged by a cam 33. 10 This latter lever is different from the others in that its upwardly extending arm has a projection in the shape of a set screw 34 which under certain conditions is designed to engage a portion of the latch-ring-carrying arm 19 so as to swing it with its attached parts upon its supporting pivot 35.

Of the needle controlling cams concerned with my invention, I have illustrated the stitch cams 36 and 37, the upper center cam 20 38, a gap closer 50, a lower center cam 40, guard cams 41 and 42, and a cam providing an annular ledge 43 directly carried by or forming part of the main cam ring. The mechanism concerned with the operation of 25 these several cams and the detail means for supporting them are fully set forth in my application above referred to, although in the drawings of this case I have shown the upper center cam 38 as slidably mounted 30 and normally forced away from the needle cylinder 4 by a compression spring 44, one end of which engages a pin 45 carried by said cam.

The position of this upper center cam is 35 determined by a cam 46 on the drum 3 acting through a lever 47 and a slidable rod or bar 48. The pin 45 on the cam 38 is designed to act on a projection 49 forming part of an arm, shown in dotted lines in 40 Figs. 1 to 3, by which is carried the gap closing member 50. The arrangement is such that a movement of the cam 38 away from the needle cylinder causes it to act on said projection so as to swing said member 45 50 into its upper position, indicated in Fig. 8, in which its upper face is on a level with the top faces of the cams 36 and 37 and closes the gap between them. Moreover the projection 49 is so formed that after having 50 been thus acted on by the pin 45, the latter rests upon it so as to effectually lock the member 50 in its elevated position.

If it be assumed that the knitting machine has been employed to knit a stocking in the 55 ordinary manner, the following operations will occur in preparing it for transfer according to my invention when the stocking has been finished, at which time the active yarn feeding finger 26 will be thrown up 60 out of action by reason of its controlling lever 31 having been engaged by the cam 33 on the drum 3 and thus being caused to act upon the jack 21. As a consequence of this 65 action, the next succeeding revolution of the needle cylinder causes all of the needles to

cast off their loops and the machine is then ready to be prepared for the transfer operation.

The lever 47 then drops from the highest portion of its cam 46 onto an intermediate 70 portion 46^a, thus permitting the rod 48 and with it the upper center cam 38, to move away from the needle cylinder sufficiently to allow the passage of the short butt needles without acting on them. Obviously 75 this movement of the cam 38 is made to occur before these needles are acted on or while the long butt needles are passing down under this cam, and as a result, when the cylinder 4 again turns so as to bring the 80 short butt needles adjacent the cam 38, the latter does not act upon them and they therefore pass along on the level of the upper edge of the ring 43.

While these short butt needles are thus 85 moving adjacent the cam 38 and before the long butt needles reach a corresponding position, said cam 38 is permitted to move under the action of its spring 45 into a fully retracted position by reason of the intermediate cam portion 46^a moving out of engagement with the lever 47, which thereupon drops onto the lowest portion of the cam, allowing a corresponding outward movement of the rod 48 and of the cam 38. 95 This outward movement of the cam 38 causes the pin 45 to act on the projection 49, so as to throw the gap-closing member 50 up into the space between the cams 36 and 37, and prevent the accidental downward movement of any of the needles. As before noted, the pin 45 when in the above noted position effectually locks the member 50 from downward movement, it being noted that the apparatus is particularly designed for use with 100 knitting machines of the free needle type. With the parts in the above positions, the continued revolution of the cylinder causes the long butt needles to be brought to and retained at the same level as the short butt 105 needles.

While now the needles are all at the same elevated level, they are too high with relation to the cylinder to give the best results in transferring, and in order to lower them the cam ring 8 is moved down by the action of the cam 12 on the drum 3 striking one arm of the lever 13, which is thus swung on its pivot so as to draw down the post 9 with its attached parts against the action of the 115 spring 11. This bodily downward movement of the cam ring with its cams puts these latter in such positions that the revolution of the cylinder 4 brings the needle butts successively into engagement with the 120 proper cam and moves them into the lowered position which I have found best for transferring.

The above described downward movement of the post 9 likewise moves downward the 130

yarn changer or latch ring 20 with its associated parts into such a position as would cause said ring to strike part of the sinker movement, and in order to prevent this, the 5 set screw 34 is provided, which just before the post 9 is drawn down, is caused to engage an adjacent portion of the arm 19 because of the action of an auxiliary cam 33^a on the lever 31, so that as shown in Fig. 3, 10 the latch ring is partially raised or tilted upwardly by this abnormal movement of the lever. By any suitable means such as is customarily used, the machine is now automatically stopped and the partly elevated latch 15 ring 20 is thrown by hand to its fully raised position, after which a loaded quill ring is placed upon the needles.

As will be understood by those skilled in the art, the lowering of the needles as above 20 described brings them into such positions with relation to the sinkers as to materially assist in guiding the quills into the proper positions relatively to said needles necessary to permit of the fabric carried by said quills 25 to be perfectly transferred. After such fabric is run off of the quills onto the needles, the quill ring is removed and in bringing the machine into condition for automatic operation, it is preferably operated by hand to a 30 sufficient extent to cause the cam 12 to disengage the lever 13, whereupon the spring 11 acts to raise the post 9 with the cam ring and its associated parts to their normal operating positions. The continued operation of 35 the machine then brings the advancing auxiliary end 46^b of the cam 46 into engagement with the lever 47 and through the rod 48 forces the upper center cam 38 toward the cylinder 4 into a position to be engaged by 40 the long butt needles, this movement of said cam occurring while the short butt needles are passing it. At the same time this inward movement of the cam 38 draws the pin 45 out of engagement with the projection 49, thus allowing the gap closing member 50 to 45 fall to its inoperative position. The long butt needles are thereafter acted on by the cam 38 and at this time said cam is moved to its full inward position by reason of the 50 main part of the drum cam 46 striking the lever 47, whereupon the needle cam 38 engages the short butt needles when next they are brought adjacent it.

While the first of the long butt needles 55 are being lowered by the cam 38, the latch ring 20 is lowered to its normal position by hand, so that the yarn finger 26 for example, is brought into such position that the yarn which it guides is engaged by the last few 60 needles of the short butt series as shown in Fig. 4, and the operator then manually presses said yarn into such position that, as shown in Fig. 5, it is certainly engaged by the first of said long butt needles just as 65 these are being lowered.

All of the various parts of the machine being now in proper normal working positions, the belt shifter handle is so moved that said machine continues to operate automatically to knit the body and foot of the stocking to the upper part thereof applied as above described. 70

I claim:—

1. The combination with a circular knitting machine having a needle cylinder, a sinker movement, a needle cam ring and a latch ring, of means for changing the vertical relation of the cam and latch rings to the cylinder; and mechanism for automatically and positively tilting up the latch ring 80 to prevent its engagement with the sinker movement.

2. The combination with a circular knitting machine having a needle cylinder, a sinker movement, a needle cam ring and a latch ring, of means for changing the vertical relation of the cam and latch rings to the cylinder; with a device for automatically moving the latch ring out of the way of the sinker movement when said ring is to be 90 lowered, the same consisting of a cam, and a lever actuated by the cam so as to be operative on the latch cam ring.

3. The combination in a circular knitting machine having a needle cylinder, a sinker movement, a needle cam ring, and a latch ring of an arm projecting from the latch ring in the form of a flat plate having side members constituting a guideway; jacks 95 slidable in said guideway; yarn feeding means controlled by the jacks; cam mechanism for actuating the jacks; pivotal means engaging said arm for supporting the latch ring; and means operative on the latch ring arm at a point below and to the rear of its 100 pivotal supporting means for automatically swinging it upward at a predetermined time.

4. The combination with a circular knitting machine having a needle cylinder, a sinker movement, a needle cam ring and a latch ring, of pivotal means for supporting the latch ring; means for vertically moving the cam and latch rings relatively to the cylinder; and means operative on the latch ring at a point below the axis of its pivotal 110 supporting means for automatically causing it to swing upwardly out of the way of the sinker movement at a predetermined time 115 in the operation of the machine.

5. The combination with a circular knitting machine having a pivotally mounted latch ring and at least one yarn guide movably carried by said ring, of a cam-controlled lever for governing the position of said yarn guide; and means for giving said lever an abnormal movement at a predetermined time to cause it to turn the latch ring on its pivot. 120

6. The combination in a circular knitting machine having a pivotally mounted latch 130

- ring, of a yarn guide mounted on said ring; means including a lever for moving the yarn guide; a cam controlling the operation of said lever; and an auxiliary cam for giving 5 the lever an abnormal movement at a pre-determined time to cause it to turn the latch ring on its pivot.
7. The combination in a circular knitting machine having a rotary needle cylinder, 10 long and short butt needles carried by said cylinder, stitch cams, and an upper center cam mounted to engage the butts of both sets of needles, of means for causing said latter cam to move successively into a position 15 to engage only the long butt needles and thereafter into a position in which it is clear of both sets of needles.
8. The combination with a circular knitting machine including a rotary needle cylinder, 20 long and short butt needles carried by said cylinder, stitch cams, and an upper center cam capable of engaging both of said sets of needles, of a cam drum; two cams thereon; and means mounted to be successively engaged by said latter cams for 25 first permitting the upper center cam to move to a position clear of the short butt needles and thereafter to a position clear of the long butt needles.
9. The combination in a circular knitting machine having a rotary needle cylinder, of 30 needles having projecting butts and operative on said cylinder; a cam movable toward and from the cylinder into and out of engagement with the needle butts; a gap-closer; means for moving said gap-closer

to a raised position when the cam is withdrawn; and means for locking the gap-closer in its raised position.

10. The combination in a circular knitting 40 machine having a rotary needle cylinder, of needles having projecting butts and operative on said cylinder; a cam movable toward and from the cylinder into and out of engagement with the needle butts; a gap-closer; means for moving said gap-closer to a raised position when the cam is withdrawn; and means controlled by said cam for locking said gap-closer in its raised position. 45

11. The combination in a circular knitting machine of a needle cylinder; needles operative therein; a cam movable into and out of position to engage the needles and having a projection; a lever mounted adjacent the 50 cam and carrying a gap-closer; with a structure carried by the cam and operative on the lever to raise the gap-closer when said cam is withdrawn from the cylinder.

12. The combination with a circular knitting 75 machine of a needle cylinder; needles operative therein; a cam movable into and out of position to engage the needles and having a projection; a lever mounted adjacent the cam and carrying a gap-closer; 65 with a structure carried by the cam and operative on the lever to raise the gap-closer when the cam is withdrawn from the cylinder and thereafter lock said lever with the gap-closer in an elevated position.

ELMER U. AMES.
